COMBINATION TOOL.

Application filed August 28, 1926. Serial No. 132,288.

This invention relates to improvements in tools for the loosening or removing of parts of mechanical structures, which said parts by reason of their peculiar form and particular location, relative to the mechanisms with which they may be associated, are incapable of being operated upon with ordinary tools.

The object of our invention is to provide a tool of this kind which is compact in form, rugged and durable, and which is capable of a relatively wide range of use.

In the present disclosure of our invention it is embodied in a service implement or device which we have designated as a combination tool. This improved combination tool is especially adapted to the purpose of the removal of engine valves, valve springs, and the like; and other mechanical parts which are difficult of access and which for one reason or another become corroded or stuck, such as the tapered terminal parts or pole pieces that are seated in the connector heads of storage batteries.

The objects of our invention are accomplished by the new construction, combination and arrangement of parts shown in the accompanying drawings and the invention is described and defined in the appended claims.

The several parts of our invention are identified by suitable characters of reference applied to them, in the different views in the drawings in which

Figure 1 is a side view of our improved combination tool in the form suitable for use in lifting valves and valve springs.

Figure 2 is a top plan view on the line 2-2 in Figure 1.

Figure 3 is a plan view on the line 3-3 in Figure 1.

Figure 4 is a view taken in the direction of the arrow in Figure 1.

Figure 5 is a cross-section view on line 5-5 in Figure 1.

Figure 6 is a cross-section view on line 6-6 in Figure 1.

Figure 7 is a cross-section view on line 7-7 in Figure 1.

Figure 8 is a side view of our improved combination tool in form for use in loosening tapered pole pieces and the like.

Our invention contemplates the providing of a C shaped device, the head member and the foot member thereof being retained in

positions opposed to each other, the head member being removably connected to the body member and the foot member being removably and hingedly connected to said body member, a sleeve loose on the body member and adapted to normally hold the foot member connection rigid and which sleeve is capable of being moved to position disengaged from said foot member connection, a cross head movable longitudinally on the head member, and a power shaft retained in said cross head and capable of being moved to and held in positions varied with relation to the said foot member.

Our improved combination tool, as shown in the present specification is of size and arrangement suitable for the general uses herein before referred to, the dimension between the head member and the foot member being about seven inches.

The head member A may be made of malleable iron and is provided with a vertical longitudinal aperture A'. This aperture is of width to permit free passing of a threaded power shaft B which is provided with a handle B'. This handle B' is connected by a knuckle pin B² and may be moved to the extended dotted line position shown in Figure 1, its corner having abutting engagement with a lug B² formed integral with the head portion of the power shaft. The said power shaft is threaded through a cross head C whose said portions, are provided with side plates C' and rest loosely in slots A² which are provided in the sides of the head member.

While we consider this cross head structure of preferred form, it will be understood that other types of construction may be used.

By this arrangement it is obvious that the power shaft may be disposed at various positions longitudinally of the head member.

At the rearward and downwardly extended portion of said head member is provided a mortised recess A³ its upper edge being shown by the dotted line in Figure 1 and designated as seat A⁴.

The foot member D is of tapered form, having the flat like toe portion D'. It is provided with a longitudinal bifurcation D² of the form and length shown in Figure 3.

At the rearwardly and upwardly extended portion of said foot member is provided a tongue D³ which has an angularly disposed face D⁴.

In the sides of the head member at its recess A^3 and in the tongue D^3 of the foot member holes are provided at such position that when the foot member is united with 5 the head member in the manner as shown in Figure 8, the said members may be secured together by a cross pin E . This cross pin has countersunk head, and its end is screwed into the threaded hole therefor in one of 10 the sides of the head member.

G designates the body member which is preferably of curvilinear form as shown in Figure 1. At its upper end is provided a tongue G' , and at its lower end is provided 15 a recess G^2 , and which said tongue G' and recess G^2 are engaged by the recess A^3 of the head member and the tongue D^3 of the foot member respectively.

The upper edge of the tongue G' registers 20 with the seat A^4 of the head member and said tongue is secured in said recess by cross pin E .

The seat G^4 of the recess G^2 registers with the face D^4 of the tongue D^3 . A cross pin H 25 having countersunk head, and which is passed through a suitable hole therefore in one side of the body member, and through a hole in the tongue D^3 , and which is threaded in the other side of the body member, 30 connects and retains the foot member hingedly at the position shown in Figure 1.

Loose on the body member is a sleeve K . This sleeve is adapted to rest normally in the lowered position and in which it so embraces the portions of the body member and of the foot member adjacent to the connection thereof, that the said parts are held securely in their relative positions shown. On the inner face of the top portion of the 35 sleeve is an integrally formed lug K' . On one side of the body member is provided a groove A^5 in which the lug K' may repose. The top of said groove A^5 is terminated in the form of a seat A^6 , thus it is seen that 40 while the sleeve may be moved freely upwardly and downwardly on said body member, the extent of its movement upwardly is limited by the lug K' coming into contact with the seat A^6 . The movement upwardly 45 of the sleeve is so limited that liability of injury to the hand while using the tool, is prevented.

Our improved tool in readiness for use in working in the engine valve or spring, is of 50 the form as shown in Figure 1. To use same the sleeve is raised and the body member is swung rearwardly on the cross pin H . Thus the upper portion of the tool is at position to avoid interference with parts 55 of the engine or block and whereby the operative is enabled to easily insert the toe D' to position underneath the spring of the engine valve stem. The foot member having been inserted or disposed at the desired 60 position, the body member is swung for-

wardly and the sleeve K is dropped to its holding position. The power shaft is then screwed against the top or head of the engine valve, thereby causing the spring to be compressed or pressed upwardly. 70

When it is desired to raise the engine valve stem, the foot member is set at engagement with the lower portion of the said valve stem, and with the cross head shifted to a location suitably aside from the central 75 position, the power shaft when screwed down, makes engagement with the top face of the engine block. The slots A^1 and A^2 in the head member are of such length that our improved tool is effective in work on 80 all valves of all types of automobile or tractor engines.

For use in the loosening of parts of 85 smaller dimensions such as the tapered pole pieces of storage batteries the body member is taken apart from the foot member and from the head member. The tongue D^3 is then disposed in recess A^3 of the head member and secured by cross pin E . The tool then appears as shown in Figure 8.

By having the handle B' adapted to be folded down to position close to the power shaft, it is possible to rotate the power shaft even though parts of associated mechanisms 90 may be closely adjacent thereto.

Our improved combination tool is capable 95 of performing its functions in locations and places which are inaccessible to ordinary tools heretofore designed for lifting valves and valve springs. The only machine work necessary in constructing our invention may be the drilling and threading of the holes for the cross pins, and drilling and threading the bore of the power shaft cross head. While considering the wide range of use to 100 which our invention may be put, the device is relatively economical of construction, and by its use, there is a saving of time, in addition to the minimizing of liability of injury to the operator's hands.

The invention is shown in the preferred 105 form of embodiment. It will be understood however that minor changes and modifications may be made in the several features and details of structure, within the scope of the invention as it is defined in the appended claims, without departing from the spirit or principle of the invention.

What we claim as our invention is:

1. A tool of the kind described comprising 110 a C shaped frame, the head portion and the foot portion thereof being in opposed relation to each other, there being a longitudinal aperture in the head portion, a cross head loosely retained in said aperture, and a power shaft retained adjustably in said cross head.

2. A tool of the kind described comprising 115 a C shaped frame, the head portion and the foot portion thereof being in opposed rela-

tion to each other, there being a longitudinal aperture in the head portion and a longitudinal bifurcation in the foot portion, a cross head loosely retained in said aperture, and a power shaft threaded through the said cross head.

3. A tool of the kind comprising a head member, a foot member, a body member removably connected at its upper end to the head member and at its lower end to the foot member, the foot member being capable of being connected directly to the head member when the body member is removed, and a power shaft capable of being held at varied positions in the said head member.

4. A tool of the kind comprising a head member, a foot member, a body member be-

ing removably connected to the head member, and removably and hingedly connected to the foot member, a sleeve loose on the body member to normally embrace and retain immovable the hinge connection of the foot member, and which said sleeve may be shifted to position apart from said hinged connection, and the foot member being capable of being connected directly to the head member connection when the body member is removed and a power shaft capable of being held at varied positions in the head member.
